UNITED STATES PATENT OFFICE.

PAUL S. HAUTON, OF ELIZABETH, NEW JERSEY, ASSIGNOR TO THE HAUTON CORPORATION, A CORPORATION OF DELAWARE.

FOUNTAIN-PEN FILLER.

Application filed March 18, 1920, Serial No. 366,793. Renewed April 15, 1921. Serial No. 461,680.

To all whom it may concern:

Be it known that I, PAUL S. HAUTON, a citizen of the United States, and a resident of Elizabeth, in the county of Union and 5 State of New Jersey, have invented a new and useful Fountain-Pen Filler, of which the following is a full, clear, and exact description.

This invention relates to fountain pens 10 and particularly to an improved construction involving a filler, having for an object the provision of means wherein a substantially full supply of ink is drawn in upon each filling operation.

15 Another object of the invention is to provide a filler which utilizes a threaded cap at one end of a fountain pen for actuating means for collapsing a flexible sack carried in the pen body.

20 A further object of the invention is to provide a filler having a collapsing mechanism for the ink sack and means co-acting with a threaded cap which will permit the cap to have an idle or dead motion for part 25 of the time during its operation in order to give the bag time to distend and draw in a full quantity of ink.

In the accompanying drawing:

Figure 1 is a longitudinal vertical section 30 through part of a fountain pen showing an embodiment of the invention.

Figure 2 is a section through Figure 1 on line 2—2.

Figure 3 is a sectional view through Figure 1 on line 3—3.

Figure 4 is a perspective view of the actuating member embodying certain features of the invention.

Figure 5 is a detail fragmentary sectional 40 view through part of the presser bar showing the connection between the bar and the actuating member.

Referring to the accompanying drawing by numerals, 1 indicates a barrel of substantially the usual kind provided with any desired kind of construction 2 which will act as a feeder for the ink and to which the pen is connected as well as the sack 3. The particular construction of member 2 and sack 3 forms no part of the present invention. Barrel 1 is threaded at the end opposite member 2 so as to receive the threaded section 4 of the cap 5. Threaded section 4 is of some appreciable length so that the cap 5 must be rotated a number of turns before

it is completely unscrewed or before it is screwed up tight against the barrel 1. A reduced neck or extension 6 extends from the cap 5 and is provided with a head 7, said neck 6 accommodating the apertured member or actuating sleeve 8 which is preferably formed integral with the actuating arm 9. The entire construction of the actuator 10 consists of the sleeve 8, the arm 9 and the connecting material which is provided with an aperture 11 for receiving a pivotal pin 11', said pin extending not only through aperture 11 but also through barrel 1. It will be noted that the sleeve 8 does not extend at right angles to the arm 9, but 70 at a slight acute angle whereby when the cap 5 is screwed up against the barrel 1 or unscrewed therefrom there is a certain lost or dead motion before the threaded section 4 or the head 7 strikes the sleeve 8 for moving the same pivotally.

As shown in Figures 1 and 4 the arm 9 extends to substantially a position on the presser bar 12 where the tongue or projection 13 extends into an aperture 14 having 80 slightly beveled walls (Figure 5) whereby bar 12 will press against the sack 3 and may freely adjust itself to receive the sack. Arm 9 is also provided with a pair of turned down sections or ears 15 and 16 85 which bear against the upper surface of the presser bar 12 while the tongue 13 is slightly upset or enlarged at its lower end in order not to move out of opening 14 so that when the arm 9 is raised from the dotted position 90 shown in Figure 1 to the full line position the presser bar will be also raised.

In operation, when the parts are in the position shown in Figure 1 and the sack 3 is empty cap 5 is unscrewed as far as possible whereupon the sack will be collapsed to its full extent. As the cap is being unscrewed the dead or loose motion between the shoulder 7 and the sleeve 8 will be first taken up after which the sleeve 8 will be 100 rocked on the pin 11' and the arm 9 will be swung downwardly to the dotted position. When this extreme collapsing position of the sack has been reached the resistance of the parts to the movement of the cap 5 will indicate that the cap is unscrewed as far as permissible. The point of the fountain pen is then submerged in a supply of ink, said fountain pen being preferably in a substantially vertical po- 110

sition, cap 5 is then screwed back into the position shown in Figure 1. As the cap is first rotated a few times the shoulder 7 will move away from sleeve 8 and permit the sack 3 to expand and raise the parts to the full line position shown in Figure 1 whereby a suction will be produced for sucking in a supply of ink. This movement of the sack and associate parts occurs an appreciable time before the cap 5 has been screwed down tight, but the operator does not know that this is taking place and consequently continues to screw cap 5 down tight against the sleeve thus allowing ample time for the rarefaction in the sack 3 to suck in a full supply of ink and completely fill or substantially fill the sack. This is of considerable advantage as the usual lever actuated fillers now in common use are operated quickly and then the pen withdrawn from the ink supply before the sack is given time to fill. This provides only a small quantity of ink while the person filling the pen thinks a full supply has been secured. For this reason frequent filling of the lever type of fillers is necessary solely on account of the ignorance of the operator of the filling mechanism. In the present construction the loose or dead motion in screwing the cap back against the barrel 1 permits ample time for the bag to become filled as the operator believes that the screwing down of the cap is necessary and will consequently hold the end of the pen in the ink supply until the cap is in a closed position.

What I claim is:

1. In a fountain pen the combination with a barrel with a collapsible bag therein of collapsing means for said bag, and a rotatable screw member for operating said collapsing means, said screw member having a predetermined dead motion in moving in both directions whereby the screw member must be rotated a number of times after the bag has become distended and thereby allow sufficient time for the filling action to take place.

2. A fountain pen filler comprising a presser bar; a pivotally mounted filling arm, and a screw member for actuating said presser bar, the connection between the screw member and the actuating arm being loose so that there will be appreciable lost motion of the screw member in both deflating and inflating.

3. In a fountain pen the combination with a distendable bag of a presser bar for collapsing said bag, an arm for actuating said presser bar, means for pivotally mounting said arm so that the arm will swing, a projection extending from said arm, and a screw cap adapted to be threaded into the end of the barrel carrying said bag, said screw cap being provided with a re-

duced portion extending therefrom merging into a shoulder adapted to engage said projection and swing the projection and said arm for collapsing the bag when the cap is unscrewed and to release said arm when rotated in the opposite direction, said shoulder being spaced a sufficient distance from the cap to permit a predetermined dead movement for causing the operation of the cap an appreciable time after the bag has been released.

4. In a fountain pen the combination with a barrel and a resilient sack, of a member for collapsing said sack, a pivotally mounted arm, an apertured member rigidly connected with said arm and extending substantially at right angles thereto, a screw cap fitting on the end of said barrel and adapted to be screwed so as to move longitudinally of the barrel, and an operating member extending from said cap through said apertured member, said operating member being appreciably smaller than the opening in said apertured member and being provided with a shouldered end adapted to overlap said apertured member so that when the cap is screwed in one direction the apertured member and parts connected therewith will be moved for collapsing the sack and when screwed in the opposite direction said apertured member and associated parts will be released, said shoulder being spaced an appreciable distance from the cap so as to allow an appreciable loose or dead motion.

5. In a fountain pen, the combination with a barrel and a resilient sack, of a presser bar for the sack, a pivotally mounted arm provided with a sleeve extending substantially at right angles to the arm, a cap threaded into the end of said barrel and movable longitudinally of the barrel when rotated, a comparatively small member projecting from said cap toward said sack, and a shoulder extending laterally from said member, said shoulder being spaced from said sleeve when the cap is in its closed position whereby when said cap is unscrewed for collapsing said sack the shoulder will not engage the sleeve until the cap has moved an appreciable distance, and when the cap is moved back to its original position the cap will be rotated an appreciable time after said sack has been released whereby time is provided for the passage of ink into the sack.

6. In a fountain pen the combination with a barrel, a resilient collapsible sack arranged therein, of a presser bar for collapsing said sack, said presser bar being formed with an opening flaring toward the side facing the sack, an actuating member mounted on the inside of said barrel formed with an actuating projection and an actuating arm, said arm being formed at its outer

end with a tongue enlarged at its extremity and fitting into the opening in said bar for holding the bar in any desired position, said actuating arm being also provided with 5 bearing members on each side of said tongue for pressing against the presser bar when the actuating member is causing the presser bar to collapse said bag, and means carried by said barrel acting on said projection for 10 causing the actuating member to collapse said sack.

7. A fountain pen having a collapsible sack and a barrel, a cap threaded into the end of the barrel in such a manner as to 15 move longitudinally of the barrel when rotated, said cap being provided with a reduced extension projecting into the barrel and merging into an annular shoulder spaced an appreciable distance from the 20 cap, an actuating member, means for pivotally connecting the actuating member with said barrel, said actuating member be-

ing formed with an apertured member surrounding said reduced extension, said apertured member being appreciably of less 25 extent lengthwise of said reduced extension than the length of said reduced extension so that the reduced extension and cap may move an appreciable distance for actuating said apertured member, said actuating member being also provided with an arm extending over said sack, and a presser bar carried by the other end of said arm for 30 pressing said sack.

8. In a fountain pen filler a presser bar 35 having an opening therein larger at one end than the other and an actuating arm for actuating said presser bar, said actuating arm having a projection larger at one end than the other, said projection loosely 40 fitting into said aperture whereby the presser bar is compelled to move with said arm.

PAUL S. HAUTON.
